United States Patent Office

Des. 230,635
Patented Mar. 5, 1974

230,635

CAMERA

John M. Mellberg, Chicago, Ill., assignor to Imperial Camera Corp., Chicago, Ill.

Filed Nov. 13, 1972, Ser. No. 306,151

Term of patent 14 years

Int. Cl. D16—01

U.S. Cl. D61—1 B

FIG. 1 is a front elevational view of a camera showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof.

I claim:

The ornamental design for a camera, as shown.
